UNITED STATES PATENT OFFICE

2,331,370

COMBINED RAZOR STROP AND RETAINER

Henry Bowden, Norfolk, Va.

Application April 15, 1943, Serial No. 483,198

1 Claim.

(Cl. 51—153)

This invention relates to strops for safety razor blades so constructed and arranged as to permit the razor to be compactly stowed away within the strop when the latter is not in use, whereby the strop and razor assembly may be packed as a unit in a traveling bag or kit so as to take up a minimum amount of space and to prevent the loss of one from the other.

An important object of my invention is to provide an improvement in the general type of strop disclosed in the U. S. patent of Henry J. Sewoster, No. 1,616,004, granted February 1, 1927, wherein the strop forms part of a carrying case providing a table for supporting a strip of leather or equivalent honing material and a manually shiftable blade carrier for drawing the safety razor blade back and forth across the strip to impart a sharp cutting edge to the blade.

More particularly my invention has for its object to provide in a strop of the above character means involving a few simple alterations in the structure of the carrying case and without substantially changing the original design and identity of the strop, whereby a safety razor may be conveniently nested within the case and held against shifting and accidental dislodgment.

Other objects and advantages will be apparent from the following detailed description of a preferred embodiment of the invention, reference being had to the annexed drawing, in which:

Figure 1 is a plan view of a strop providing razor retaining means;

Figure 2 is a longitudinal cross-sectional view taken on the line 2—2 of Fig. 1;

Figure 3 is a transverse cross-sectional view taken on the line 3—3 of Fig. 1; and

Figure 4 is a detail cross-sectional view showing the razor blade holder and carrier forming parts of the strop.

In the drawing is illustrated a strop for sharpening safety razor blades corresponding substantially to the device disclosed in the Sewoster Patent No. 1,616,004, above-mentioned, to which patent reference is made for a more detailed description of the construction and operation of the device. For present purposes it is sufficient to state that the strop comprises an elongated metal case 1 of flat, box-shaped construction having a closed bottom 2 and a top 3. The top is cut away so as to provide transversely disposed shelves 4 located at opposite ends of the case and an intermediate table 5 for supporting a strip of leather or similar honing material 6. A razor blade carrier 7 extends between and slidably engages opposite sides of the case. A razor blade

B (Fig. 7) to be sharpened is adapted to be clamped within a holder 8 and freely and rockably suspended on the carrier, extending through a slot therein, in such a manner that by sliding the carrier back-and-forth with the fingers the blade is repeatedly drawn across the honing strip 6 supported on the table 5. The openings between the ends of the table and the shelves 4 allow the blade and holder to swing to vertical position following each traverse of the table so that when the direction of travel of the carrier is reversed the opposite side of the blade edge is presented to the honing strip. A few strokes of the carrier is sufficient to impart a keen edge to the blade. For retaining the honing strip 6 in place, its ends are tucked under flanges 4a extending inwardly from the sides of the box and contiguous with the shelves 4.

In order to adapt the strop to use as a retainer for a safety razor R, I propose to provide one or both of the shelves 4 with a transversely extending slot 9 sufficient in size to receive and accommodate the head 10 of the razor when the latter is introduced under the shelf and one side of the head projected upwardly, as indicated in Figs. 1 and 2. In furtherance of this object, the adjacent end of the table 3 is cut away to provide a recess 9a which allows the handle 11 to drop down below the level of the table, when the end of the honing material is lifted, and rest within a notch 12 cut in a down-turned flange 13 contiguous with an end of the table. The position of the razor when fully inserted in the case 1 is best illustrated in Fig. 2. By replacing the end of the honing strip under its retaining flanges so that it overlies the razor handle, the razor is held in place. Also by shifting the carrier 7 to a position so that it overlies the razor handle and the honing strip, additional security to hold the razor handle is added, especially when a rubber band encircling the case, or other suitable means is used to prevent the carrier 7 from shifting off the handle. The case may be provided with a removable cover (not shown) if desired, as suggested in the Sewoster patent. The assembly takes up only a small amount of space in a grip, suitcase or kit, and obviates the necessity of another box or case being carried as a container for the razor and blade; and as another advantage, it reduces the likelihood of either the razor, the blade or the honing device therefor being misplaced or separated.

To remove the razor from the case, it is only necessary to slide the carrier 7 free of the razor handle 11, to lift the end of the honing material,

and then to tilt the case to cause the handle to swing outwardly so that it may be grasped by the fingers and the head 10 disengaged from the slot 9.

Because the device permits carrying the razor, blades and hone in one small compact container, it is well adapted to the use of soldiers on campaign or in active service where a saving of space in their packs or baggage is of especial importance.

While I have described my invention by way of example with particular reference to the form of strop disclosed in the above-identified patent of Sewoster, it will be apparent that the invention is capable of broader application, and that the strop may take other forms than that specifically illustrated as described herein without departing from the spirit of my invention as defined by the following claim.

I claim:

The combination with a razor strop comprising a box-shaped, hollow case having a closed bottom, a table for supporting a strip of honing ma-

terial extending transversely across the top of said case and having its ends spaced from the ends of the case, a shelf extending transversely across the top of said case and located intermediate the table and an end of the case, and a carrier adapted to rockably support a safety razor blade, said carrier being manually slideable longitudinally of the table so as to draw said blade back-and-forth across the honing strip; of retaining means for a safety razor, said retaining means comprising a slot in said shelf so constructed and arranged as to allow the head of a safety razor to be inserted under the shelf and one side thereof projected upwardly through said slot, a longitudinally extending recess within said table adapted to pass the handle of said razor and a rest for engaging and limiting the downward movement of said handle, whereby when the razor is inserted in said slot and recess the carrier may be shifted over the recess to prevent accidental dislodgment of the handle therefrom.

HENRY BOWDEN.
